DENTAL CABINET

Jack H. Levey, Los Angeles, Calif.

Application July 18, 1952, Serial No. 20,666

Term of patent 7 years

(Cl. D24—1)

To all whom it may concern:

Be it known that I, Jack H. Levey, a citizen of the United States, residing at 1064 Hi Point, Los Angeles, county of Los Angeles, State of California, have invented a new, original, and ornamental Design for a Dental Cabinet, of which the following is a specification, reference being had to the accompanying drawing froming part thereof:

Fig. 1 is a perspective view of a dental cabinet showing my new design;

Fig. 2 is a side elevational view thereof the other side of the cabinet being of the same appearance with the same side handle;

Fig. 3 is a plan view thereof; and

Fig. 4 is a fragmentary perspective view of the upper portion of the dental cabinet with the cover open.

I claim:

The ornamental design for a dental cabinet, substantially as shown and described.

JACK H. LEVEY.
